UNITED STATES PATENT OFFICE

2,380,423

COVERALL

Israel L. Freedman, Washington, D. C.

Application December 5, 1941, Serial No. 421,783

1 Claim. (Cl. 2—79)

(Granted under the act of March 3, 1883, as amended April 30, 1928; 370 O. G. 757)

The invention described herein, if patented, may be manufactured and used by or for the Government for governmental purposes, without the payment to me of any royalty thereon.

This invention relates to combination outer garments, which are more particularly referred to as coveralls, that are adapted to be used by machinists and others engaged in work which necessitates a garment of like construction, to protect them from the grease and dirt with which they come in contact while plying their trade.

The object of the invention resides in providing an outer garment which will be comfortable to wear and which may be readily adjusted to fit the wearer, according to his height and the length of his legs.

Another object of the invention is to provide an outer garment in which the trouser portion and waist portion are joined together at the waistline and further to provide inside supporting means connected to the trousers at the waistline at the rear of the garment, whereby the length of the legs of the trouser portion may be varied in front of the garment by an adjustment that can be quickly and easily made.

Another object of the invention is to provide a gas protective garment having a gas-proof fly construction or closure that by its structure will prevent the entrance of poison gas into the garment at the crotch.

Mustard gas, which is used during any military engagement, is a very irritating gas and if it enters between the openings of the garment at the crotch will incapacitate the wearer so that he will need hospital care. This garment, by the use of such a fly closure, prevents the entrance of such a gas, thereby making the garment an unusually important addition to the soldier's wardrobe, since it can also be used as a gas protective garment as well as a machinist's garment.

With the above and other objects and advantages in view the invention consists of features of construction, arrangement and operation of parts which will appear in the specification and be finally pointed out in the claim.

While the preferred embodiment of the invention is shown, it will be understood that slight changes in form and minor details of construction may be effected without departing from the spirit of the invention, hereinafter more fully described in the specification and illustrated in the accompanying drawings.

wherein similar characters and references in the several figures indicate identical parts.

Fig. 1 is a front view of the garment embodying the invention.

Fig. 2 is a front view showing the front open and the supporting means attached to the rear of the garment at the waistline.

Fig. 3 is a fragmentary perspective view of the crotch.

Fig. 4 is a sectional view on line 4—4 of Fig. 3.

Fig. 5 is a sectional view on line 5—5 of Fig. 1.

Fig. 6 is a sectional view on line 6—6 of Fig. 1.

Fig. 7 is a perspective view of the waist of the garment showing the supporting means.

Fig. 8 is a diagrammatic view of the garment in adjusted position, and

Fig. 9 is a diagrammatic view of the garment before adjustment has been made.

Following the usual procedure of distributing garments in the Army, men who have short legs are sometimes given garments of the type described in which the legs are long or the crotch is lower than usual and much discomfort is experienced unless the legs are shortened, either by cutting off a portion of the legs or turning the legs up at the cuff, which makes a very bulky arrangement at the bottom of the trousers, continually getting in the wearer's way or becoming unfolded. The rule of distribution usually followed does not permit the cutting of the legs, since when the garments are laundered they are not returned to the previous wearer but are sent to a general distributing point for distribution, and it is very seldom that the same garment is worn twice by the same man.

This invention was developed in order to remedy this great inconvenience on the part of the soldiers, and a supporting means was therefore provided whereby the garment can be easily adjusted to any leg length.

As previously stated, another inconvenience caused by the old type of garment was the position in which the crotch of the garment came with respect to the wearer. If it was too low it would bind the wearer's legs and he would have difficulty in moving, unless he pulled the garment higher when required. As stated, this drawback is also remedied when the legs are adjusted, since the raising of the trouser portion of the garment not only shortens the leg but brings the crotch into the desired position required by the individual wearer.

This raising of the trouser portion also gives greater fullness in the rear portion of the waist, so that it does not bind on the wearer's back or

become tightened, pulling on the garment and thus interfering with the wearer's freedom of movement.

For the purpose of illustration there is shown the outer garment 10 having a waist portion 11 and a trouser portion 12. The trouser portion 12 is formed with legs 13 and an outer waistband having tying ends 14 extending completely around the outside of the garment 10. The waist portion 11 is divided in the front to form a continuation of the fly of the trouser portion, thus permitting the wearer to easily don the garment or take it off.

The fly of the trouser portion is better shown in Figs. 3 and 6, wherein 15 designates the outside portion of the fly on the right-hand side of the garment and 16 the inside portion. The inside portion 16 is an extra piece of material which is attached to the inside of the garment along the entire length of the opening on the right-hand side. The inside portion 16 is provided with buttons 17 which are adapted to coact with buttonholes 18 on the left-hand portion 19 of the trouser.

The outside portion 15 is not provided with buttonholes at the crotch but from the waistline to the neck of the garment buttonholes 18 are provided to form a double closure on the waist portion 11, this being more clearly shown in Fig. 5.

Referring more particularly now to Fig. 7, there is shown a support or suspender 20, which is attached to the inside of the garment at the

waistline, and has two elongated straps 21 which extend over the shoulders and down along the inside of the garment to the waistline. These straps 21 are retained in position by loops 22 and 5 when it is desired to raise the crotch 23 and shorten the legs 13 the strap is pulled tight and tied, as shown at 24.

There is provided, therefore, a garment that can be adjusted so that it is comfortable for all types of men, a garment that is gasproof, and one that will easily adjust itself to all the particular uses for which it is intended.

It is thought that since those skilled in the art will readily understand the operation of this garment, it will not be necessary to go into further detail.

Having thus described the invention, what is desired to secure by Letters Patent is:

An outer garment comprising a coat-like waist portion and a trouser portion provided with a fly, a permanent connection between the meeting edges of the waist and trouser portions, a single and uncovered buttonhole flap at one side of the fly, an imperforate button-flap on the opposite side of the fly, and an imperforate flap overlapping and co-extensive with the button-flap and stitched to the top, bottom, and side of the button-flap remote from the free edge of the latter, whereby a pocket is formed for the reception of the buttonhole flap when the garment is in use.

ISRAEL L. FREEDMAN.
